UNITED STATES PATENT OFFICE.

JOHN H. EARLES, OF DENVER, COLORADO.

FIRE-ALARM.

SPECIFICATION forming part of Letters Patent No. 351,753, dated November 2, 1886.

Application filed April 24, 1886. Serial No. 200,114. (No model.)

To all whom it may concern.

Be it known that I, JOHN H. EARLES, a citizen of the United States, residing at Denver, in the county of Arapahoe and State of Colorado, have invented a new and useful Improvement in Fire-Alarms, of which the following is a specification, reference being had therein to the accompanying drawings, in which similar letters refer to corresponding parts.

1c My invention relates to improvements in fire-alarms; and the object of my improvements is to provide an automatic fire-alarm for use in dwelling-houses, hotels, business-blocks, &c.

15 Figure 1 is a view of the mechanism by means of which the alarm mechanism shown in Figs. 2 and 3 is operated. Fig. 2 is a side view, and Fig. 3 an end view, of the alarm mechanism. Fig. 4 shows an attachment by 2c means of which the alarm is sounded from different floors of the same building. Fig. 5 shows the piston forming part of the mechanism shown in Fig. 1.

In the drawings, *a* is a receptacle containing mercury, mounted upon a suitable support attached to the wall of the room.

b is a piston working within the tubular or upper portion of receptacle *a*. The top part of piston *b* contains holes *b'*, and is attached to a lever, *c*, by means of a pin, as shown. The object of holes *b'* is to regulate the depth to which piston *b* penetrates tube *a*. Lever *c* has a fulcrum, *c'*, and is connected with another lever, *d*, having a fulcrum, *d'*. The inner extremities of levers *c* and *d* are so beveled that when both levers are in a horizontal position, or in a position nearly horizontal, the inner extremities will be in contact and both levers will remain at rest until the outer extremity of lever *c* is raised sufficiently to disconnect the two levers. The outer extremity of lever *d* is so fashioned that a weight, *e*, may be hung thereon when said lever is in a horizontal position.

40 45 *f* is a case which guides the direction of weight *e* as it falls after being released from lever *d*.

g and *h* are levers connected by means of a notch in lever *g*, one extremity of lever *h* being fashioned to fit within said notch. Said levers remain in contact until the outer ex-

tremity of lever *g* is depressed sufficiently to disconnect them, as shown. These levers are provided with fulcrums *g'* and *h'*.

i is a weight hung upon lever *h*. To weight 55 *i* is attached one extremity of a wire, *j*, the other extremity of said wire being attached to a pawl, *k*, provided with pivot *k'*.

l is a shaft journaled within a suitable supporting-frame, and provided with cog-wheel *m* 60 and ratchet-wheel *n*, which are made fast to the same and turn with it. Pawl *k* engages ratchet-wheel *n*.

o is a shaft journaled within a supporting-frame, and provided with small cog-wheel *p* 65 and escapement-wheel *r*, which are made fast thereon and turn with it. Wheel *p* meshes within wheel *m*.

s is an escapement, provided with hammer *s'* and working upon a shaft, *s'*. Escapement *s* 70 is operated by wheel *r*.

t is a gong, against which hammer *s'* strikes.

u is a weight attached to rope *v*, which is wound around a drum formed by the enlargement of shaft *l* between its journals.

In describing the operation of my improved device, I will designate the mechanism shown in Fig. 1 as the "motor" and the mechanism shown in Figs. 2 and 3 as the "alarm." 75

The motor is fastened to a suitable frame attached to the wall of the room. The alarm may be at any distance therefrom within the same building, the two being connected by the wire *j*, which is provided with guide-pulleys or other supports, *j'*, placed at suitable distances. A button, *j''*, is placed upon wire *j*, so as to come in contact with one of the supports, leaving the wire slack between it and weight *i* when suspended on lever *h*. Button *j''* prevents wire *j* from being drawn tight by any force acting between it and the alarm. 85

Piston *b* may be set by the use of thermometer *w*, so as to sound the alarm-gong at any desired temperature. Thus, reckoning that piston *b* must be raised fifteen degrees in order 95 to disconnect levers *c* and *d*, we adjust the piston so that its lower extremity shall remain at a point, as indicated by the thermometer, 15° below the temperature at which we desire the gong to sound.

In describing the operation of my improved alarm, I will suppose that a fire originates in

the room where the motor is placed. As the temperature of the room increases the mercury rises in tube *a*, and lifts piston *b*, thereby disconnecting levers *c* and *d*. Weight *e* then drops upon lever *g*, thus releasing lever *h*, which permits weight *i* to drop, said weight being heavy enough to disconnect pawl *k* and ratchet-wheel *n*. Weight *u* then sets shaft *l* in motion, which operates the alarm mechanism, causing hammer *s*² to beat gong *t*.

One of my motors should be placed in a central position on each floor of the building. Only one alarm need be used, the same being placed in that portion of the building where it will be most readily heard.

A wire leading from the motors placed upon the different floors of the building is attached to a ring, *x*, to which the wire connected with pawl *k* is also attached. Ring *x* is so placed within the room containing the alarm that it may be readily observed. The wires *y* are attached to ring *x*.

To each wire *y* is attached a covering, *y'*, placed over a figure, denoting the number of the floor where the motor is located with which said wire is connected.

A fire having started in the vicinity of the motor located on any particular floor, the wire *y*, connected with the motor on said floor, is pulled sufficiently to sound the alarm and at the same time to remove the covering *y'* from the figure indicating the number of the floor where the fire has originated.

What I claim as my invention, and desire to secure by Letters Patent, is—

1. In a fire-alarm, the combination of receptacle *a*, containing mercury, said receptacle being provided with a neck, *a'*, piston *b*, fashioned to work within neck *a'*, lever *c*, provided with fulcrum *c'* and attached to piston *b*, as

shown, lever *d*, provided with fulcrum *d'* and connected with lever *c*, as shown, weight *e*, hung upon lever *c*, lever *g*, provided with fulcrum *g'* and notch *g''*, the outer extremity of said lever being placed directly beneath weight *e*, lever *h*, provided with fulcrum *h'* and connected with lever *g*, as shown, weight *i*, hung upon lever *h*, and wire *j*, attached to weight *i* at one extremity, the other extremity being connected with suitable mechanism for sounding the alarm, substantially as described.

2. In a fire-alarm, the combination of a motor consisting of a receptacle, *a*, containing mercury and provided with a neck or tube, *a'*, piston *b*, fashioned to fit within said neck *a'*, and provided with holes *b'* in its upper portion, lever *c*, provided with fulcrum *c'*, and attached to piston *b*, as shown, lever *d*, provided with fulcrum *d'*, and connected with lever *c*, as shown, weight *e*, hung upon lever *d*, lever *g*, provided with fulcrum *g'* and notch *g''*, its outer arm being placed directly beneath weight *e*, lever *h*, provided with fulcrum *h'*, and connected with lever *g*, as shown, weight *i*, hung upon lever *h*, and an alarm consisting of pawl *k*, to which is attached one extremity of wire *j*, as shown, ratchet-wheel *n*, connected with pawl *k* and working upon shaft *l*, gear-wheels *m* and *p*, working upon shafts *l* and *o*, respectively, escapement-wheel *r*, working upon shaft *o*, and escapement *s*, connected with said wheel *r* and working upon shaft *s'*, said escapement being provided with hammer *s''* and gong *t*, substantially as described, and for the purpose set forth.

JOHN H. EARLES.

In presence of—

J. B. WILLSEA,
F. I. WILLSEA.
